[57] CLAIM

The ornamental design for a combined food and beverage cooler, substantially as shown and described.

DESCRIPTION

FIG. 1 is a top perspective view from one end of a combined food and beverage cooler showing my new design with the carrying handle folded into a storage position.

FIG. 2 is a top perspective view thereof taken from the end opposite FIG. 1 showing the carrying handle in its operative position.

FIG. 3 is a top plan view thereof showing the carrying handle in the position of FIG. 1.

FIG. 4 is an end elevational view thereof showing the end from which the perspective view of FIG. 1 is taken.

FIG. 5 is a side elevational view of one side thereof, the opposite side being identical.

FIG. 6 is an end elevational view thereof showing the end opposite the end shown in FIG. 4.

FIG. 7 is a bottom plan view thereof.

FIG. 1.FIG. 2.FIG. 3.FIG. 4.FIG. 5.FIG. 6.FIG. 7.
